UNITED STATES PATENT OFFICE

JAMES E. JAGGER, OF HOLYOKE, MASSACHUSETTS, ASSIGNOR TO HOLYOKE PLUSH COMPANY, OF HOLYOKE, MASSACHUSETTS, A CORPORATION OF MAINE.

DESIGN FOR WOVEN FABRIC.

46,833.

Specification for Design.

Patented Jan. 5, 1915.

Application filed September 15, 1914. Serial No. 861,898. Term of patent 7 years.

To all whom it may concern:

Be it known that I, JAMES E. JAGGER, a citizen of the United States, residing at Holyoke, county of Hampden, State of Massachusetts, have invented a new, original, and ornamental Design for Woven Fabric, of which the following is a specification, reference being had to the accompanying drawing, forming a part hereof.

The figure is a plan view of a section of woven fabric showing my new design.

The design comprises a series of stripes 1, 1, 1, etc., extending in the same general direction across the fabric. These stripes are of irregular width as shown and each stripe at irregular intervals is formed into a reverse curve. Each reverse curve is as to its general curvature complementary to the ones adjacent it. Referring, for example, to the stripe 1 at the right edge of the figure, three of these reverse curves are shown, one

extending from 2 to 3, another from 3 to 4, and another from 4 to 5, and it will be noted, for example, that the reverse curve 3 to 4 is complementary in general curvature both to the reverse curve 2 to 3 and to the reverse curve 4 to 5. The irregular arrangement causes these reverse curves to be out of alignment in a direction transverse to the general direction of the stripes, and thus to produce the effect shown.

The stripes are shown as embossed or depressed in a pile fabric so as to be beneath the general surface of the body of the fabric.

I claim:

The ornamental design for a woven fabric having the stripes as shown.

JAMES E. JAGGER.
